[57] CLAIM

The ornamental design for a combined writing instrument and folding pocket measure, as shown and described.

DESCRIPTION

FIG. 1 is a top plan view of a combined writing instrument and folding pocket measure showing my new design;

FIG. 2 is a bottom plan view thereof;

FIG. 3 is a front elevational view thereof;

FIG. 4 is a rear elevational view thereof;

FIG. 5 is a left end elevational view thereof;

FIG. 6 is a right end elevational view of FIG. 3;

FIG. 7 is a perspective view thereof with the folding pocket measure partially open;

FIG. 8 is a side view of FIG. 7 with an end portion broken away; and

FIG. 9 is a plan view of the design, on a reduced scale, with the folding pocket measure extended to its maximum length.
